(57) **CLAIM**

The ornamental design for a rechargeable lamp, as shown and described.

DESCRIPTION

FIG. 1 is an upper front perspective view of a rechargeable lamp;

FIG. 2 is a lower front perspective view thereof;

FIG. 3 is an upper rear perspective view thereof;

FIG. 4 is a top view thereof;

FIG. 5 is a bottom view thereof;

FIG. 6 is a left side view thereof;

FIG. 7 is a right side view thereof;

FIG. 8 is a front view thereof; and,

FIG. 9 is a back view thereof.

The broken lines depict portions of the rechargeable lamp that form no part of the claimed design.

1 Claim, 9 Drawing Sheets(56)
